UNITED STATES PATENT OFFICE.

FREAD FREADREAZEA, OF LOUISVILLE, KENTUCKY.

ATTACHMENT FOR CARS.

SPECIFICATION forming part of Letters Patent No. 758,519, dated April 26, 1904.

Application filed December 19, 1903. Serial No. 185,836. (No model.)

To all whom it may concern:

Be it known that I, FREAD FREADREAZEA, a citizen of the United States, residing at Louisville, in the county of Jefferson and State of Kentucky, have invented new and useful Improvements in Attachments for Cars, of which the following is a specification.

This invention relates to attachments for cars, especially express-cars and the like, wherein are deposited valuables, such as money-safes; and the primary object of the same is to so protect a car of this class by the addition thereto of a metal guard-box and projecting tower in communication therewith at an elevation and also inclosing fastening means coöperating with different portions of the car that the latter may be effectually defended by a single person against the inroads and nefarious practice of robbers, the improved means also being operative in part to hold a prisoner outside of the compartment or guard-box wherein the valuables are contained at the will of the defender of said compartment.

A further object of the invention is to have in addition to a guard compartment or box a holding means for the retention of a prisoner and an elevated tower which will permit an occupant of the compartment or box to have a commanding view of an entire train, including the engine and tender, without liability of dangerous exposure and with advantage in freeing a train from a holdup by confederates stationed at points along the length of the train during the attempt of one or more of the accomplices of the confederates to gain access to a car or cars to relieve the latter of valuables.

The invention consists in the further novel construction and arrangement of the several parts, which will be more fully hereinafter set forth.

In the drawings, Figure 1 is a horizontal section of the end portion of a car embodying the features of the invention. Fig. 2 is a longitudinal vertical section of the same. Fig. 3 is a transverse vertical section through the car end. Fig. 4 is a detail elevation of a movable imprisoning-partition. Fig. 5 is an enlarged horizontal section of a portion of one end of the car, showing means operative from the interior of a guard compartment or box

for locking the car-door to prevent opening of the latter. Fig. 6 is a detail perspective view of a portion of the car-door and casing of the guard compartment or box, showing means for closing the car-door after the latter has been opened and locking the same.

Similar numerals of reference are employed to indicate corresponding parts in the several views.

The numeral 1 designates a portion of an express or other analogous car of any suitable construction and having an end entrance-door 2 leading to the usual end platform 3. The door 2 is hinged, as usual, and opens inwardly. In the corner of the car adjacent to the hinged edge of the door 2 is a steel or other suitable metal compartment or guard-box 4, which extends vertically from the floor of the car to the top of the latter and communicates with an upper inspection tower or turret 5, projecting through and above the top of the car and having a series of port-holes 6 therein, covered by slide-doors 7, movable in guides 8 on the inner surface of the walls of the tower or turret. As many of the port-holes and slide-doors coöperating therewith may be used as found necessary, so that an occupant of the turret or tower may have full commanding view of a train from end to end and whereby also a firearm may be aimed in any direction in relation to the train.

Each slide-door 7 has a drop latch-bar 9, which also serves as a handle in operating such door, and to lock the door closed the said drop latch-bar falls between a pair of pins 10, projecting inwardly from the inner surface of the tower or turret side or end below the lowermost guide 8, said pins being so disposed that when the door is fully closed the drop latch-bar will move between the same.

The guard compartment or box 4 is provided with an entrance-door 11, which may be locked on the inside by a suitable latch 12. In this compartment or box at a suitable point is a winding-drum 13, with which a cable or analogous device 14 coöperates and runs through a suitable conduit 15 over guide-pulleys 16 and across the car at a suitable distance from the door 2, where it is attached to one end of a collapsible imprisoning-partition 17, suspended by hangers 18 from an upper track-

rail 19, the said partition being of a grated type, as clearly shown by Fig. 4, and readily operative to convert one end of the car-body into what may be termed an "imprisoning cell or inclosure."

To render the function of the imprisoning-partition 17 effective, it is obvious that means must be provided for quickly closing and locking the door 2 against movement. This means

- 10 consists of a rod 20, movably attached to the inner side of the lower end of the door 2 and freely shiftable through a slot 21 in the bottom of the side of the inclosure or box 4 at a point adjacent to the door, the end of the rod
- 15 20 within the compartment or box being bent at an angle to form a locking-pin 22, adapted to be inserted in a pin-hole 23 in the floor of the car within said inclosure or box. Through the medium of this rod 20 the door can be
- 20 quickly closed after it has been opened and locked, and following this operation the drum 13 may be conveniently operated to throw the imprisoning-partition 17 across the car, and thus form an imprisoning-inclosure.
- 25 Another advantageous feature in the improved construction is means for preventing the door 2 from being opened, and consists of a sliding bolt 24, inclosed within a portion of the car end adjacent to the hinged edge of the
- 30 door and adapted to be shifted to enter a socket 25 in said door edge, as clearly shown by Fig. 5, the outer end of the sliding bolt being bent at an angle to form a handle or grip 26, movably projecting through a slot 27
- 35 in the outer end wall of the compartment or box 4 and engageable from the interior of the latter to quickly operate said bolt.

The compartment or box 4 will also have at regular intervals, as may be found desirable,

- 40 port-holes for firearms similar to those arranged in the tower or turret 5 in order that the interior of a car may be fully covered in defensive operations, the said port-holes and means for closing the same being shown by
- 45 Figs. 2 and 3 and having the same reference-numerals applied thereto as the analogous devices in the tower or turret.

Although the invention has been particularly described in connection with cars or vehicles, it will be understood that the same structure may be used in banks and other places of a like nature.

The improved structure is comparatively simple and may be readily applied to cars now in use without requiring a reorganization of the latter.

While the attachments are particularly intended for use in express-cars, it will be understood that they may be employed in other vehicles, and to accommodate various applications changes in the proportions and dimensions, as well as the minor details, may be resorted to without in the least departing from the spirit of the invention.

Having thus fully described the invention, 65 what is claimed as new is—

1. The combination with a car, having a door opening thereinto, of a metal guard-inclosure located adjacent to said door, and a slide-bolt concealed within the car structure 70 and solely operative from within the said inclosure to engage the door and lock the latter against opening movement.

2. The combination with a car, having a door opening thereinto, of a metal guard-inclosure adjacent to the door, and a closing means for the door pivotally connected to the latter operative from within the closure and movable to lock the door closed after it has been opened.

3. The combination with a car, having a door opening thereinto, of a guard-inclosure adjacent to the door, a rod pivotally attached to the lower portion of the door and freely shiftable through the adjacent wall of the inclosure and adapted to be located within the latter to prevent opening movement of the door, and means for locking the rod against movement and controllable from within the guard-inclosure.

4. The combination with a car, having a door opening thereinto, of a guard-inclosure located adjacent to the door and provided with a turret extending upwardly through and above the top of the car, the inclosure and 95 turret having closable port-holes, means operative from within the inclosure to shut and lock the door closed, and an imprisoning-partition transversely movable across the car and also operative from within the inclosure to 100 form an imprisoning-cell at one end of the car.

5. The combination with a car, having a door, of a guard-inclosure within the car in proximity to the door, means operative from within the inclosure to shut and lock the door 105 closed, and a collapsible imprisoning-partition movable transversely across the car and also operative from within the inclosure.

6. The combination with a car, of a metal guard-inclosure therein, and an imprisoning-partition shiftable transversely across the car at a distance from and operative from within the inclosure to form a cell in the car.

7. The combination with a car, having a door opening thereinto, of a metal guard-inclosure adjacent to the door, a slide-bolt concealed within the structure of the car and arranged to engage the door, said bolt being operative from within the inclosure, and a closing means pivotally attached to the door and movable through one wall of the guard-inclosure.

In testimony whereof I affix my signature in presence of two witnesses.

FREAD FREADREAZEA.
